CLAIM

The ornamental design for a foundation re-bar support, as shown and described.

DESCRIPTION

FIG. 1 is a perspective view of the invention; FIG. 2 is a top view thereof; FIG. 3 is a front view thereof; and, FIG. 4 is a side view thereof.

Dashed lines are used to show the environment and other shading lines are used, neither of which comprise any of the claimed invention.

The front side elevation view is identical to the back side elevation view, and the left side elevation view is identical to the right side elevation view.

1 Claim, 4 Drawing Sheets
